UNITED STATES PATENT OFFICE.

ALOIS GASSENHUBER, JR., OF SOUTH MILWAUKEE, WISCONSIN.

PUMP.

1,381,115.

Specification of Letters Patent. Patented June 14, 1921.

Application filed October 19, 1920. Serial No. 417,895.

To all whom it may concern:

Be it known that I, ALOIS GASSENHUBER, Jr., a citizen of the United States, and resident of South Milwaukee, in the county of Milwaukee and State of Wisconsin, have invented certain new and useful Improvements in Pumps; and I do hereby declare that the following is a full, clear, and exact description thereof.

10 My invention refers to improvements in compound air pumps and has for its primary object to provide a pump of this general character, the cylinders of which can be telescoped, one within the other, when 15 the device is not in use so as to provide compactness, and a further object is to simplify the valve construction, whereby the life of the valve is increased to the maximum and the tendency of such valves to leak is also 20 overcome, due to the direct action of valves of the simple hat packing type.

It is also an object of the invention to provide a pump which can be manipulated with the least possible power to develop the 25 desired compression of fluids, the compression being effected on both strokes of the piston.

With the above and other minor objects in view, the invention consists in certain peculiarities of construction and combination of mechanical elements, as are hereinafter described and subsequently called for in the claims.

In the drawings,

35 Figure 1 represents a sectional elevation of a pump embodying the features of my invention, the cylinders of which are shown in their inactive nested position, whereby the length of the pump is materially shortened for convenience in carrying or storing, the section being indicated by line 1—1 of Fig. 5.

Fig. 2 is a detail sectional view of the upper head of the pump showing the inner compression cylinder adjusted to its working position.

Fig. 3 is a cross section of the pump, the section being indicated by line 3—3 of Fig. 1.

50 Fig. 4 is an outside elevation of the pump upon a reduced scale, showing parts broken away and in section, and also showing the compression cylinder distended and locked in its operative position.

55 Fig. 5 illustrates an elevation of the pump in its inactive position, similar to that shown

in Fig. 1 and it particularly illustrates the compression piston leading to a source of storage or a receiver.

Referring by characters to the drawings, 60 1 represents a base head which closes the lower end of an intake cylinder 2, the upper end of the same being closed by head 3. The upper head is centrally apertured for telescopic union with a compression cylinder 4, which cylinder is of comparatively much smaller area than the fluid intake cylinder 2. Both ends of the compression cylinder are opened and the upper end thereof is connected to a fluid distributing pipe 5 65 by suitable couplings 6, and mounted upon the couplings or fittings 6 is a gage 6' which directly communicates with the pipe 5 and thereby swivelly discloses the pressure maintained in pipe 5 or a suitable portion 70 of storage, such for example as a pneumatic tire. The lower end of the compression cylinder is provided with a flange or guided collar 7, which collar is spaced from the walls of the cylinder 2 to permit fluid to 75 freely pass therebetween. When the compression cylinder is withdrawn or distended with relation to the cylinder 2, for working purposes it is locked in such distended position by any suitable means, as for example in this instance, a set screw 8 is used, which set screw is in threaded union with the upper head 3 of the intake cylinder, and is adapted to impinge against the outer 80 wall of the cylinder 4, as best shown in 85 Fig. 2.

To prevent rotary movement of the cylinder and to also give the same rigidity when it is distended, I provide a pin 9 which projects upwardly from the collar 7, the same being arranged to enter a recess 9' in the upper head 3, as shown.

Reciprocatively mounted in the compression cylinder is a hollow piston rod 10, the lower end of which has secured thereto a 100 centrally apertured disk 11, to which disk is fitted a hat packing 12 of flexible material and the same is secured to the disk by a ring 12'. The hat packing extends downwardly so as to contract when the piston 105 rod is moved toward the upper head of the cylinder and to expand snugly of the walls thereof when the feed piston is moved downwardly. The upper end of the piston rod is similarly provided with a flange ring 13 110 carrying a hat packing gasket 14, the outer edges of which extend upwardly and against

the walls of the compression cylinder, whereby a simple tight joint is effected.

In addition to this piston head structure, I also provide an apertured cage 15 which is in threaded union with the end of the hollow piston, the said cage being provided with a ball 15', which serves as a check valve and prevents air under pressure from the discharge pipe connections from entering 10 the hollow piston rod.

In order to reciprocate the hollow piston 10, I provide a pair of tie rods 16, which rods are secured to the lower valve head by a threaded connection between their ends 15 and the flange 11. The tie rods extend longitudinally of the cylinder 2 and are guided at their upper ends by means of apertures 17 which are formed in the head 3. Thus the tie rods extend through the head and 20 are connected to a reciprocative handle or cross head 18 by suitable nuts, which are in threaded union with the rods, it being understood that the cross head 18 is apertured for reciprocative movement upon the 25 compression cylinder. Thus the tie rods and all reciprocative parts are guided and firmly held against side strain. In order to further guide the parts and prevent twist of the cylinder 4, the collar 7 thereof is provided with peripheral notches which have frictional engagement with the tie rods, as 30 best shown in Fig. 3.

From the foregoing description, it will be seen that when the apparatus is to be put 35 into working position, the set screw 8, as in clamping engagement with the nested compression cylinder, is also distended, due to its open end coming into engagement with the flange 11 of the piston head mechanism. 40 The compression cylinder will then assume the position shown in Fig. 2, and the set screw will be employed to lock the same in this position. A downward movement of the piston mechanism will thus cause the 45 air in the cylinder 2 to be forced through the hollow piston head into the compression cylinder 10, whereby this volume of air is compressed to a predetermined degree, due to the different areas of the two cylinders. 50 Upon the upstroke of the cross head 18, the packing gasket 12 will contract slightly and permit atmospheric air to pass between the end walls of the cylinder 2, whereby said cylinder is filled and while this filling action 55 is taking place, obviously the air or fluid above the upper piston head associated with the piston 10 will be again compressed to the maximum volume, it being understood that the check valve mechanism 15 and 15' will 60 prevent its leakage back into the pump mechanism.

It will also be observed that the simple hat packing 14 in the upper end of the hollow piston simply serves as a piston packing

only, and is held tightly against the walls 65 of the compression cylinder by the air pressure thereabove. Hence, the only active parts subject to leakage would be the hat packing gasket 12 and the check valve mechanism 15 and 15', and obviously these two 70 valve mechanisms being of such simple form, practically no appreciable wear will come upon them.

Thus it will be seen that a simple and practical double-acting pump of the compound type is produced, wherein the ground structure is such as to provide the minimum of wear and thus overcome the serious object 75 to devices of this character, bearing in mind that the telescopic feature is one of the important elements of the invention wherein compactness is obtained and the compound feature of the pump is thus produced in a simple manner.

I claim:

1. A compound pump comprising an air intake cylinder having upper and lower heads, a compression open ended cylinder in telescopic union with the intake cylinder, the same having one end extended through the cylinder head, means for locking the compression cylinder in its distended working position with relation to the intake cylinder, a hollow reciprocative piston rod mounted in the compression cylinder, a valve head 95 at its lower end engageable with the intake cylinder walls, a check valve control head carried at its upper end engageable with the compression cylinder walls, longitudinally disposed tie rods carried by the lower piston rod head, the same extending through the upper head of the intake cylinder and actuating means connecting the rods.

2. A compound pump comprising an intake cylinder having a lower closed head and an upper head, an open ended compression cylinder in telescopic union with the intake cylinder, means for locking the compression cylinder to distended position with relation to the first cylinder, an open ended hollow piston rod having an upper head in reciprocative union with the compression cylinder and a lower valve head in reciprocative union with the intake cylinder, a check valve mounted in the hollow piston for preventing back flow of air from the compression cylinder, a tie rod extending from the lower head of the hollow piston and projecting through the upper head of the intake cylinder and means secured to 110 the outer end of the tie rod for actuating the hollow piston.

In testimony that I claim the foregoing I have hereunto set my hand at South Milwaukee, in the county of Milwaukee and 125 State of Wisconsin.

ALOIS GASSENHUBER, JR.
